UNITED STATES PATENT OFFICE.

HANS BAERBALCK, OF HAMILTON, OHIO, ASSIGNOR TO THE HAMILTON MACHINE TOOL COMPANY, OF HAMILTON, OHIO, A CORPORATION OF OHIO.

RELIEVING MECHANISM FOR ENGINE-LATHES.

No. 870,759.

Specification of Letters Patent.

Patented Nov. 12, 1907.

Application filed February 3, 1906. Serial No. 299,292.

To all whom it may concern:

Be it known that I, HANS BAERBALCK, a citizen of Germany, residing at Hamilton, Ohio, have invented a new and useful Improvement in Relieving Mechanisms for Engine-Lathes, of which the following is a specification.

My invention relates to relieving mechanisms for engine lathes, of the class adapted for turning fluted reamers or other tools with relieved cutting edges, and the 10 objects of my improvement are to provide means to reciprocate the tool carrier in different horizontal angles of adjustment; to adjust the tool carrier in the direction of its reciprocating movement; to provide means to automatically advance or retard the movement of reciprocation of the tool carrier in relation to the speed of rotation of articles to be turned to register with a predetermined helical line thereon; to provide adjustable means to adapt the attachment to relieve the cutting edges of either straight or tapered articles having a pre- 20 determined number of either straight or helical flutes, and to adapt the mechanism to a wide variety of engine lathes. These objects are attained in the following described manner as illustrated in the accompanying drawings, in which:—

25 Figure 1, is a plan of portions of an engine lathe embodying my improvement; Figs. 2 and 3, longitudinal sections respectively on the lines *a—a*, and *b—b* of Fig. 1; Fig. 4, a transverse section on the line *c—c* of Figs. 1 and 2; Fig. 5, a plan with parts broken away and parts 30 in section of the speed changing gears, the rear portion of the carriage, and of the taper attachments; Fig. 6 a side elevation of the quadrant arm; and Fig. 7, a vertical section on the line of shaft 38 looking from the rear.

In the drawings, 1 represents the shears of an engine 35 lathe, 2 the tool carriage mounted thereon and provided with sliding plate 3 which carries nut 4 in engagement with the transverse feed screw 5 for adjusting said plate longitudinally on the carriage. The front end portion of said screw is splined in sleeve 6 which is journaled in the front wall of the carriage and provided with handle 7. Rotative plate 8 is pivotally mounted on sliding plate 3 and secured in rotative adjustment thereon by 40 means of clamping bolts 9 whose heads are movable in a circular tee groove 11 formed in the sliding plate there- 45 under.

Plate 12 mounted to reciprocate longitudinally between guides 13 formed on the rotative plate is formed with an opening 14 in its rear end over the center of the rotative plate and with depending lug 15.

50 Bolts 16 adjustably secured in the front wall of the rotative plate are extended loosely through respective openings formed in lug 15 and each provided on the rear end with a fixed collar 17.

Coiled springs 18 compressed between the lug and the 55 collars encircle the respective bolts 16.

Carrier 19 formed with a transverse tee slot 21 for the tool post (not shown) is mounted on the rotative plate to slide parallel with plate 12 and directly thereover. Said carrier is secured to and longitudinally adjustable on said plate by means of auxiliary feed screw 22 being 60 journaled in the front wall of the carrier and adjustably engaging with nut 23 carried by the plate.

Vertical shaft 24 engaging with driven shaft 25 by means of miter gears 26 is journaled in the axis of the rotative plate. Cam 27 is removably keyed thereon to rotate within opening 14 formed in plate 12. Nose 28 is removably secured to said plate within the rear side of the opening therein by means of screws 29. The yielding exertion of springs 18 on lug 15 maintains the plate with said nose in continuous contact 70 with the face of the cam in its rotation. The action of the cam on the nose moves plate 12, together with the tool carrier gradually in a rearward direction until the highest point of the cam is passed, when the action of the springs reciprocates them quickly in the opposite direction. Said driven shaft 25 is journaled in bearing 31 formed on the under side of sliding plate 3, and also in sleeve 32 mounted in carriage 2 and is movable longitudinally with said sliding plate.

Long spiral gear 33 splined on the projecting rear portion of shaft 25, meshes with a similar short spiral gear 34 which is secured on sleeve 35. Said sleeve is journaled in a bearing 36 formed in the extended rear portion of carriage 2, and is prevented from longitudinal movement therein by means of the spiral 85 gear 34 and the collar 37 being secured on its opposite ends in contact with said bearing. Driving shaft 38 parallel with the shears is splined in said sleeve and journaled near one end in bracket 39 which projects rearwardly from the lathe bed. Gear 41 secured on 90 said shaft is driven from the back gear (not shown) of the lathe at predetermined speeds through the intermediate removable and interchangeable speed changing gears 42 which are carried on quadrant arm 43 whereby they may be maintained in adjusted en- 95 gagement with the said back gear in the ordinary manner.

Guides 44 and 45 pivotally secured at one end on bracket 46 which projects rearwardly from the lathe bed, are independently adjustable at the other end in different horizontal angles on opposite sides of plate or bracket 47 which is projected rearwardly from the lathe bed opposite the head stock (not shown) thereon. Bolts 48 movable in slots 49 serve to maintain said respective guides in adjusted angular positions. Slides 105 51 and 52 movable longitudinally along the respective guides are each pivotally secured to corresponding transverse carriage slides 53 and 54 which are longitudinally movable in respective channels 55 and 56 formed in the extended rear portion 57 of the carriage 2. 110

Carriage slide 53 carries a raised bearing 58 wherein the rear end of the transverse feed screw 5 is swiveled and movable longitudinally with the slide without interfering with its rotative movement by means of sleeve 6 wherein it is splined.

Carriage slide 54 is provided with a bracket or yoke 59 which spans the spiral gear 33 lengthwise and controls its longitudinal position in relation to spiral gear 34 regardless of the longitudinal movement of driven 10 shaft 25 whereon it is splined.

When the guides 44 and 45 are parallel with the movement of the carriage on the shears, the carriage slides may be immovably secured to the carriage by means of bolts being inserted through holes 61 formed in the 15 rear end of the slides and holes 62 formed to register therewith through the rear cross bar 63 of the carriage extension.

In operation, the movement of sliding plate 3 for turning tapering articles is controlled in the usual manner by the adjusted angle of guide 44 to the direction of movement of the carriage on the shears. Slide 51 in guide 44 carries carriage slide 53 which controls the longitudinal movement of transverse feed screw 5 swiveled in bearing 58 thereon, sliding plate 3 being adjustably secured on said feed screw by means of nut 4 20 is longitudinally movable thereby together with the rotative plate thereon.

For turning straight articles carriage slide 53 may be immovably secured to the carriage by the insertion of 30 a bolt or pin through holes 61 and 62 in the respective slide and carriage and either disconnecting said carriage slide 53 from slide 51 or adjusting guide 44 parallel with the movement of the carriage.

By means of the speed changing gears 42 any desired 35 predetermined speed of driving shaft 38 may be secured and transmitted to the cam 27 through the spiral gears 34 and 33, shafts 25 and 24 and miter gears 26. During each rotation of the cam, by reason of its contact with nose 28, plate 12 together with the carrier 19 40 is gradually moved in a rearward direction and quickly returned by the action of springs 18. The rotative speed of either the straight or tapered article to be turned should be so predetermined that the successive straight flutes thereon shall register in time with the 45 return movement of plate 12 and that the gradual advance of the tool by the action of the cam may occur between the flutes to relieve the cutting edges by a gradually deepening cut behind them.

For relieving the cutting edges of straight or tapered 50 articles having helical or spiral flutes, the additional adjustment is required of guide 45 at such angle to the shears as will cause the yoke on the carriage slide 54 to move the long spiral gear 33 longitudinally on driven shaft 25 in relation to spiral gear 34 in continuous mesh 55 therewith. Owing to the opposite angles of the teeth of said spiral gears at their points of contact any longitudinal movement of one gear in relation to the other will vary the relative speed of rotation of driven shaft 25 and the cam 27 driven thereby from the speed of 60 driving shaft 38. The acceleration or retardation in the time of the reciprocation of plate 12 thus obtained may be regulated to correspond with the pitch of the spiral flute on the article to be turned.

The rotative plate may be rotatively adjusted to 65 cause the reciprocation of plate 12 to occur in a line

perpendicular to the surface of tapered articles in the lathe, or in a line at any horizontal angle to the axis of the lathe centers.

Having fully described my improvement what I claim as my invention and desire to secure by Letters Patent of the United States is:

1. In a lathe, a carriage, a tool carrier thereon, a driven shaft, means mechanically connected therewith for reciprocating the carrier, a driving shaft, spiral gears engaging the driven shaft therewith, and means constructed and arranged to be actuated by the movement of the carriage for shifting one of said gears longitudinally in relation to the other. 75

2. In a lathe, the combination of a driving shaft, a carriage provided with a tool carrier, a driven shaft carried by the carriage and adapted to be actuated at a predetermined speed by the driving shaft, means mechanically connected therewith for reciprocating the tool carrier, and means constructed and arranged to be actuated by the movement of the carriage for varying the speed of the 85 driven shaft.

3. In a lathe, the combination of a driving shaft, a carriage movable parallel therewith and provided with a tool carrier, a driven shaft carried by the carriage, means mechanically connected with the driven shaft for reciprocating the tool carrier in synchronism therewith, gears connecting the driving with the driven shaft, and means constructed and arranged to be actuated by the movement of the carriage for changing the speed of one of said shafts 90 in relation to the other. 95

4. In a lathe, the combination of a carriage provided with a tool carrier, a driving shaft, a driven shaft actuated thereby and movable with the carriage, connections with the driven shaft for moving the tool carrier, and means constructed and arranged to be actuated by the 100 movement of the carriage for changing the speed of the driven in relation to that of the driving shaft.

5. The combination of a tool carrier, a driven shaft, means actuated thereby adapted to reciprocate said carrier, a driving shaft, spiral gears adapted to transmit motion therefrom to the driven shaft, and means adapted to move one of said gears longitudinally in relation to the other to effect a variation in the relative speeds of the 105 shafts. 105

6. In a lathe, the combination of a driving shaft, spiral gears arranged to be actuated thereby, a carriage provided with a tool carrier, means actuated by said spiral gears from the driving shaft for reciprocating the tool carrier at a predetermined rhythm, and means constructed and arranged to be actuated by the movement of the carriage for 110 changing the relative position of the spiral gears in parallel planes, whereby the rhythm of movement of the tool carrier is varied. 115

7. In a lathe, the combination of a carriage provided with a tool carrier, and with a driven shaft, a driving shaft, spiral gears connecting the driven shaft therewith, means actuated by the driven shaft for reciprocating the tool carrier in synchronism with the driving shaft, and means constructed and arranged to be actuated by the movement of the carriage for changing the relative position of the gears in parallel planes, whereby the movement of the carrier will be changed in relation to the speed of the driving shaft. 120

8. In a lathe, the combination of a carriage provided with a tool carrier, a driving shaft, spiral gears actuated thereby, means mechanically connected with said gears for moving the tool carrier, and means constructed and arranged to be actuated by the movement of the carriage for changing the relative speed of said gears. 125

9. In a lathe, a carriage provided with a tool carrier and with a driven shaft, means mechanically connected with the driven shaft for reciprocating the carrier, a driving shaft, spiral gears engaging the driven shaft therewith, and means constructed and arranged to be actuated by the movement of the carriage for shifting one of said 130 gears longitudinally in relation to the other said gear. 135

10. In a lathe, a carriage, a driving shaft parallel therewith, a spiral gear splined thereon and movable with the

carriage, a guide connected to the lathe bed and adjustable in different angles to said shaft, a slide movable therein with the carriage, a spiral gear carried thereby parallel with the guide and engaging with the former gear, a driven shaft splined therin and carried with the carriage, a tool holder, and connections from the driven shaft to move the tool holder.

11. In a lathe a driving shaft, a lathe carriage movable parallel therewith, a short spiral gear splined on said shaft and movable with the carriage, a driven shaft carried with the carriage, a long spiral gear splined thereon

and engaging with the said short gear, a guide secured to the lathe bed and adjustable in different angles to the driving shaft, a slide movable therein with the carriage, a connection from said slide to the long spiral gear, said slide being adapted to move the long gear longitudinally on the driven shaft for maintaining it in a line parallel with the guide.
